METHOD AND DEVICE FOR DISTRIBUTING
GASES OR VAPORSDuncan B. Williams, Glen Ridge, N. J., assignor
to Carbide and Carbon Chemicals Corporation,
a corporation of New York

Application July 29, 1932, Serial No. 625,799

10 Claims. (Cl. 102—29)

The invention relates to the distribution or dispersion of gases or vapors, particularly those of a noisome or irritating nature. My invention includes methods and devices for effecting the 5 distribution of such gases or vapors, all as more specifically hereinafter described.

Various substances which are capable of producing gases or vapors have been proposed for use in offense and defense or protection. The 10 substances commonly used are generally either of the group of lacrimatory or sternutatory (tear- or sneeze-inducing) substances, and lacrimatory substances are usually employed. These materials are ordinarily known as tear 15 gases, and used in the form of tear gas bombs or grenades. The chief use of tear gases is in police work, and to a lesser extent in the safeguarding of business establishments and private dwellings.

20 A satisfactory tear gas should possess certain properties; for example, it should be efficient as a lacrimator or irritant; easily handled, transported, and used; dependable in function; and substantially free from permanent toxic effects; 25 and it should present no great hazard of fire or explosion. The device in which the tear gas or gas producing substance is used is of importance although its nature is usually controlled by the substance used therein. The device or 30 bomb should be simply constructed, certain to operate, easily transported, handled and thrown or projected, and incapable of reuse (for example, thrown back at the original user before taking effect).

35 Prior to this invention no device or substance was known which possessed the foregoing qualities to a substantial degree. The principal object of my invention is to provide a novel, safe, and efficient method for distributing irritating 40 gases, and to provide novel combinations of materials to be employed in the new method. Another object is to provide an economical, simple, efficient, and dependable device for effecting the distribution of irritating gases, fumes, vapors, or 45 similar fluids. The above and other objects will be apparent from the following description together with the accompanying drawing, in which

Fig. 1 is an elevation, partly in section, of an improved device embodying my invention, and 50 Fig. 2 is a section through containers suitable for confining the active ingredients to be used in the device.

55 Referring to the drawing, the device may comprise two frangible containers 10 and 11 which are preferably made of glass and hemispherical

in form as shown in Fig. 2. The containers 10 and 11 are adapted to have fluid substances confined therein by sealing them, as shown at 12, or by threaded screw caps or any suitable closure means. The frangible containers 10 and 11 may be retained within a casing 13 formed of sheet metal or any convenient material. The casing 13 preferably is spherical in form and somewhat larger than the spherical form obtained by placing together the containers 10 and 11. The casing 13 may be conveniently made in two hemispherical portions which are secured together in the final assembly by welding them as shown at 14, or by providing the halves with screw threads, by soldered or crimped joints, or in any other 15 manner. Apertures 15 are provided at intervals in the casing 13 to permit gases, fumes, or vapors to escape therefrom, and inwardly projecting portions 16 are also provided at intervals upon the interior of the casing 13. The projections 16 are adapted to hold the containers 10 and 11 in position in the assembled device and to assist in fracturing the containers 10 and 11 when the casing 13 is subjected to impact. The 20 projections 16 may be formed by deforming portions of the casing 13 or they may be separate metallic portions secured to the interior of the casing 13, or formed in any other suitable manner.

The substances to be contained in the containers 10 and 11 may be the same in each container or different substances. In a preferred embodiment of my invention, crotonaldehyde is used as a lacrimator and is placed in one of the containers while a material, such as a tetrahalide 35 of the elements of group 4 of the periodic table, preferably silicon tetrachloride or titanium tetrachloride, which is capable of spontaneously producing a visible fume or smoke when released into the atmosphere, is placed in the other container. The fume or smoke producing agent used 40 is selected from those materials which are substantially non-reactive with crotonaldehyde.

Crotonaldehyde is normally a liquid which, though boiling at 104° C., has exceptional surface 45 wetting tendencies so that it spreads rapidly over a surface and is readily and spontaneously vaporized. The vapors of crotonaldehyde are colorless and have a powerful irritating odor. It is a strong lacrimator even in minute concentrations, 50 and in appreciable quantities is so irritating as to render presence in its vapors unbearable. Exposure to the vapors of crotonaldehyde is not attended by serious after effects, and its toxicity is 55 much less than that of the most commonly em-

ployed lacrimatory substance now in use. The lower explosive limit of crotonaldehyde vapor in air is 2.21% by volume, and this amount is many times the quantity required to render a given 5 space entirely uninhabitable; hence, the danger of fire or explosion with crotonaldehyde is not material.

In many cases it is advantageous to use a tear gas which is visible; for example, it is advantageous for the user of the gas to know the course and extent of the distribution of the gas or vapor, and it is a distinct advantage in police work for dispersing unwanted gatherings to use a visible gas because of the psychological effect of visibly 10 apparent fumes or smoke. Therefore, it is generally preferable to use a fume or smoke producing agent with crotonaldehyde, or the fume or smoke producing agent may be used alone. For example, a distinguishing mark or color may be 15 imparted to the containers to be used in the device to identify the contents as either crotonaldehyde or silicon or titanium tetrachloride. The bomb may be made so that the two portions are separably secured together by a threaded joint or the 20 like, and the bomb may be used with two containers of crotonaldehyde or of the smoke producing agent or with one of each as desired. A convenient means of identification may comprise 25 a dye added to the liquid.

As one illustration of the use of the invention, two fluid ounces each of crotonaldehyde and silicon tetrachloride were simultaneously liberated in a room having a volume of 1200 cubic feet. The temperature of the room was about 25° F. The 30 effect of the crotonaldehyde was instantaneous and lacrimation was produced in the observers. The course and extent of the distribution of crotonaldehyde was visibly apparent by reason of the white smoke or fume produced by the silicon tetrachloride. All observers not equipped 35 with gas masks were compelled to quit the room within 30 seconds after the crotonaldehyde liquid was liberated. This quantity of crotonaldehyde amounted to 0.112 pounds per 1000 cubic feet of air in the room.

In another test, crotonaldehyde was atomized with air and forced into the room described above through a keyhole. In this test the amount of crotonaldehyde was exactly one half that used in 50 the first case and the results were much the same; the observers were forced to resort to gas masks within 37 seconds after the initial injection of crotonaldehyde.

My invention provides a novel and efficacious 55 method for distributing a normally invisible irritating gas or vapor in a manner which renders visible the course and extent of its distribution by simultaneously and positively liberating at substantially the same point a spontaneously vaporizable substance capable of producing an irritating gas which is normally invisible and a substance which spontaneously produces a visible fume or smoke. There is thus produced an immediate intimate intermixing of the irritating 60 gas and the visible fume or smoke at the point of liberation and vaporization, so that the smoke completely and accurately indicates the course and extent of distribution of the irritating gas. Variations of the invention may provide for the 65 liberation of either substance alone as desired. The above described embodiments are deemed sufficient to enable those skilled in the art to practice the invention and its modifications.

I claim:—

75 1. Method for distributing a normally invisible

irritating gas in a manner which renders visible the course and extent of the distribution of said gas which comprises simultaneously and positively liberating crotonaldehyde at substantially the same point with a tetrahalide of an element of group 4 of the periodic table which is capable of spontaneously producing a visible fume or smoke and which is substantially nonreactive with crotonaldehyde, so that there is produced an immediate intimate intermixing of the vaporized crotonaldehyde and the visible fume or smoke at the point of liberation. 5

2. Method for distributing a normally invisible irritating gas in a manner which renders visible the course and extent of the distribution of said gas which comprises simultaneously and positively liberating from separate containers and at substantially the same point, crotonaldehyde with a substance selected from the group consisting of silicon tetrachloride and titanium tetrachloride, so that there is produced an immediate intimate intermixing of the invisible crotonaldehyde vapor and the visible tetrachloride vapor at the point of liberation. 10

3. Method for distributing a normally invisible irritating gas in a manner which renders visible the course and extent of the distribution of said gas which comprises simultaneously and positively liberating crotonaldehyde with silicon tetrachloride from separate containers and at substantially the same point, so that there is produced an immediate intimate intermixing of the invisible crotonaldehyde vapor and the visible silicon tetrachloride vapor at the point of liberation. 15

4. Method for distributing a normally invisible irritating gas in a manner which renders visible the course and extent of the distribution of said gas which comprises simultaneously and positively liberating crotonaldehyde with titanium tetrachloride from separate containers and at substantially the same point, so that there is produced an immediate intimate intermixing of the invisible crotonaldehyde vapor and the visible titanium tetrachloride vapor at the point of liberation. 20

5. Device for distributing gases, fumes and smoke, which comprises frangible containers confining spontaneously vaporizable substances which are capable of producing the fluids to be distributed, a casing surrounding said frangible containers, said casing being provided with apertures for the passage of said fluids therethrough, and being provided with inwardly projecting portions in contact with said frangible containers adapted to hold said containers in position and to assist in fracturing said containers when said casing is subjected to impact. 25

6. Device for distributing gases, fumes and smoke, which comprises two frangible containers confining spontaneously vaporizable substances which are capable of producing the fluids to be distributed, a metallic casing surrounding said frangible containers, said casing being provided with apertures for the passage of said fluids therethrough, and being provided with inwardly projecting portions in contact with said frangible containers adapted to hold said containers in position and to assist in fracturing said containers when said casing is subjected to impact. 30

7. Device for distributing gases, fumes and smoke, which comprises two hemispherical frangible containers confining spontaneously vaporizable substances which are capable of producing the fluids to be distributed, a metallic cas- 35

- ing spherical in form comprising separably secured portions surrounding said frangible containers, said casing being provided with apertures for the passage of said fluids therethrough, and 5 being provided with integral inwardly projecting portions in contact with said frangible containers adapted to hold said containers in position and to assist in fracturing said containers when said casing is subjected to impact.
- 10 8. A device for distributing an irritating gas simultaneously with a visible fume or smoke, which comprises frangible containers separately confining an irritating gas producing agent and a fume or smoke producing agent, a casing 15 surrounding said frangible containers, said casing being provided with apertures for the passage of gases or vapors therethrough, and being provided with inwardly projecting portions in contact with said frangible containers adapted to 20 hold said containers in position and to assist in fracturing said containers when said casing is subjected to impact.
9. A device for distributing an irritating gas simultaneously with a visible fume or smoke, 25 which comprises two hemispherical frangible containers separately confining an irritating gas
- producing agent and a fume or smoke producing agent, a metallic casing spherical in form surrounding said frangible containers, said casing being provided with apertures for the passage of gases or vapors therethrough, and being provided with inwardly projecting portions in contact with said frangible containers adapted to hold said containers in position and to assist in fracturing said containers when said casing is subjected to impact. 5
- 10 10. A device for distributing an irritating gas simultaneously with a visible fume or smoke, which comprises two hemispherical frangible containers separately confining an irritating gas producng agent and a fume or smoke producing 15 agent, a metallic casing spherical in form comprising two portions secured together surrounding said frangible containers, said casing being provided with apertures for the passage of gases or vapors therethrough, and being provided with 20 integral inwardly projecting portions in contact with said frangible containers adapted to hold said containers in position and to assist in fracturing said containers when said casing is subjected to impact. 25
